UNITED STATES PATENT OFFICE.

OTTO W. SCHAUM, OF PHILADELPHIA, PENNSYLVANIA.

SHUTTLE.

SPECIFICATION forming part of Letters Patent No. 619,232, dated February 7, 1899.

Application filed April 11, 1898. Serial No. 677,129. (No model.)

To all whom it may concern:

Be it known that I, OTTO W. SCHAUM, a citizen of the United States, residing in Philadelphia, county of Philadelphia, and State of Pennsylvania, have invented certain new and useful Improvements in Shuttles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of my present invention is to provide a shuttle for swivel-shuttle or ribbon looms with an increased bearing surface and also to provide a shuttle-block for said shuttle having a race-way conforming in shape to the increased bearing-surface of said shuttle, whereby the further dropping or depressing of the nose of the shuttle is prevented and besides insuring a more perfect working of said shuttle increases its durability and also the durability of the shuttle-block. A further object is to provide a shuttle with a runner having its grain in the direction of the edges of the runner and its nose constructed of a separate piece of wood and secured to said runner.

The invention consists in the improved shuttle, its shuttle-block, and in the combination and arrangement of the various parts, substantially as will be hereinafter more fully described, and finally embodied in the clauses of the claim.

In the accompanying drawings, Figure 1 is a top plan view of my improved shuttle; Fig. 2, an underneath view of Fig. 1; Figs. 3 and 4, rear elevations of the shuttle; Fig. 5, an enlarged sectional view on the line xx of Fig. 1; and Fig. 6, a view similar to Fig. 5 and illustrating the shuttle in the raceway of my improved shuttle-block, the latter being shown in section and partly broken away.

The shuttle which is illustrated in the drawings is intended for a ribbon-shuttle, and consists of the runner a and the nose b , which are glued or otherwise secured together, as at c . The runner is provided in its under side with a toothed rack d of ordinary construction and at its outer lower portion with

an elongated flange or projection e , rectangular in cross-section, as clearly illustrated in Figs. 5 and 6 of the drawings.

55

The upper portion of the runner a is provided at or near its inner edge with an elongated rectangular groove f , while the remaining top portion is flattened, as at g , and at right angles to the back h of the runner.

60

The shuttle-block i contains the shuttle-race m , the top n of which is adapted to be engaged by the bearing-surface g of the runner, while the downwardly-extending projection o of the shuttle-block i conforms in shape to and is adapted to engage the rectangular channel or groove f in said runner.

The lower portion of the shuttle-race conforms in shape to the lower portion of the runner and can be of any suitable design or 70 construction.

From the foregoing it can be seen that the runner of the shuttle furnishes an increased bearing-surface with the top portion of the shuttle-race, as its flattened portion g is in engagement with the flattened portion n in said block, by which arrangement the dropping of the shuttle-nose is prevented, which is of the greatest importance during the process of weaving, as will be manifest to those 80 familiar with the art. It will also be seen that owing to the fact that the runner is spaced from the rear wall of the race the contact between the runner and the walls of the race is minimized and confined only to points where 85 such contact is necessary in accordance with the principles of my invention.

As heretofore stated, the shuttle is constructed of two pieces—that is to say, of the runner a and of the nose b —which are glued 90 or otherwise secured together, the nose being straight and the runner having been previously bent to the proper circle from a piece of straight-grained wood. The nose or front portion of the shuttle may also be of straight-grained wood, and thus furnishes, together with its runner, a shuttle which is very durable and strong, (as there is no cross grain to it,) especially on the points, which are apt to chip off.

95
100
I do not intend to limit myself to the precise construction shown and described, as various alterations can be made without changing the scope of my invention; but

What I claim as new, and desire to secure by Letters Patent, is—

1. A shuttle consisting of a substantially straight shuttle-nose having its grain running straight and longitudinally thereof, and a curved runner secured to said nose and having its grain parallel to its curve throughout its entire length, substantially as described.
2. A shuttle consisting of a substantially straight shuttle-nose having its grain running straight and longitudinally thereof, and of a curved runner secured to the nose, having its grain parallel to its curve throughout its entire length, and provided in its top portion with an elongated rectangular groove and with adjoining flattened bearing-surfaces, said bearing-surfaces and the base of the elongated groove being parallel with the curve of the grain, substantially as described.
3. The combination of shuttle-blocks each having a shuttle-race therein whose upper wall presents a flat widened surface, and a

shuttle comprising a substantially straight nose having its grain running straight and longitudinally thereof and a curved runner secured to said nose and having its grain parallel to its curve throughout its entire length, said runner having a flat widened upper bearing-surface extending from its free edge inwardly toward the nose, and arranged to impinge squarely against said wall, and said runner being formed to closely fit between the upper and lower walls of the race adjacent its line of connection with the nose and spaced from the rear wall of said race, substantially as described.

In testimony that I claim the foregoing I have hereunto set my hand this 6th day of April, 1898.

OTTO W. SCHAUM.
